CHIN MASSAGER

Samuel L. McNair, Fullerton, Calif., assignor to The Songrand Corporation, a corporation of Missouri

Filed Mar. 9, 1965, Ser. No. 84,168

Term of patent 14 years

(Cl. D83—1)

Fig. 1.

Fig. 2.

Fig. 3.

Fig. 4.

Fig. 5.

FIG. 1 is a perspective view of a chin massager embodying my design;

FIG. 2 is an end elevational view of same; the view of the other end is substantially the same as this view;

FIG. 3 is a top plan view of same;

FIG. 4 is a side elevational view taken from the side opposite of FIG. 1; and

FIG. 5 is a bottom plan view of same.

I claim:

The ornamental design for a chin massager, as shown and described.
